UNITED STATES PATENT OFFICE

2,096,803

AUTOMATIC DETECTOR

George Hantopoulos, New York, N. Y.

Application August 28, 1935, Serial No. 38,232

1 Claim. (Cl. 200—82)

The purpose of this invention is to provide a device which is particularly adapted for use on internal combustion engines and the like by which the internal operation of the engine may be determined from a remote point so that improper firing or combustion of any cylinder may readily be indicated.

The invention is a relatively small device that may be installed on the cylinder of an engine which is operated by the pressure of the cylinder and which is adapted to close or open a circuit to indicate said pressure and the circuit may be connected through a series of electric lights so that when the pressure reaches a predetermined degree it will light the light to which it may be connected.

Many devices have been provided for indicating the operation of an internal combustion engine or the like and these operate from the intake manifold or exhaust and also from different parts of the engine, however it has been found desirable to provide an indicator that may be used directly upon the cylinders of the engine so that the actual pressure in each cylinder may readily be determined while the engine is in operation.

The object of the invention is therefore to provide a simple and efficient device which is capable of operating in high temperatures, that may be installed on the individual cylinders of an engine, which will automatically open or close a circuit while the engine is in operation.

Another object is to provide an individual unit that may readily be installed on a motor vehicle engine without interfering with the operation of the engine, which automatically opens or closes an electric circuit.

A further object is to provide a device that may be operated by the pressure of the explosion of an internal combustion engine cylinder or the like which may readily be installed and which may close a circuit when the pressure reaches a predetermined amount.

And a still further object is to provide a device operated by pressure for opening and closing circuits, that may be installed on the cylinder of an engine, which is of a simple and economical construction.

With these ends in view the invention embodies a relatively small plug of about the same size as a spark plug having means thereon for opening and closing a circuit, which may be screwed into a threaded opening in the cylinder of an

engine and connected to an electric light bulb or a series of bulbs.

Other features and advantages of the invention will appear from the following description taken in connection with the drawing, wherein:

Figure 1 is a view showing a typical arrangement of the device with the plug shown in section and the remaining parts in elevation.

Figure 2 is a side elevation of the device shown in Figure 1.

Figure 3 is a view similar to that shown in Figure 1 showing an alternate design in which parts are shown in section.

Figure 4 is a plan view of the device shown in Figure 3.

In the drawing the device is shown as it may be made wherein numeral 1 indicates the plug, numeral 2 a pressure operated element, and numeral 3 a light that may be lighted as the element 2 operates to complete a circuit.

The plug 1 may be of any type and design and may be of any size. In the design shown the plug is made with a hexagonal head having a threaded shank 4 with an opening 5 therein and the element 2 which is substantially flat,

is formed with a base 6 adapted to be secured in the upper end of the opening 5, and this element extends over substantially forming a circle with the opposite end thereof pivotally connected to a lever 7 by a link 8 with the end of the member 2 connected to the link by a pin 9, and the opposite end of the link connected to the lever 7 by a pin 10. The element 2 forms an expanding member, and with one end fixed, or held in the plug, the other will be moved outward by the opening movement of the expanding member, as the pressure is increased, thereby operating the lever 7 to make a contact to complete a circuit which will light the lamp 3, that may be located at the instrument board or at any particular point, when the ignited gases explode. The lever 7 is pivotally mounted on a stand 11 by a pin 12. This is only a typical arrangement as this device may be arranged in any manner and may be open as shown or enclosed or formed in any manner. The stand 11 is mounted upon the nut at the upper end of the plug 1 by bolts 13 and the upper end is provided with a hub 14 in which a screw 15 is mounted in an insulating member 16. The insulating member 16 extends through the hub and the end of a wire 17 may be held upon the screw 15 by a nut 18 and with washers 19 and 55

50

55

20 on each side of the wire. It will be understood however that this connection may be formed in any manner and the screw 15 which is positioned to be engaged by the end of the 5 lever 7 may be mounted by any means or arranged in any manner so that as the lever 7 is operated by the expanding of the member 2 the end thereof may be engaged thereby.

10 The contact wire 17 may extend to one terminal of the lamp 3 and the other terminal may be directly connected to the ground or may be connected by a wire 21 to the plug 4 through a battery 22. It will be understood however that the electric circuit may be arranged in any manner and any means may be used for providing 15 electric current.

20 The design shown in Figures 3 and 4 is substantially the same except that a piston and cylinder is used instead of the circular member 2, however either device may be used on the cylinder of an engine and operated by the pressure thereof. It is possible that the device shown in Figure 3 may be more adapted for extreme temperatures, where the thin walls of the device 2 may 25 not be advisable.

25 In the design shown in Figures 3 and 4 a plug 23 is used as a base member and this is provided with a threaded shank 24 and has a cylindrical opening 25 extending through the shank and a piston 26 is slidable in the opening. A "U" shaped bracket 27 is held on the upper surface of the plug 23 by screws 28 and a contact point 29 is mounted in an insulating member 30 in the upper end of the bracket and this member is mounted on a screw 31 having a nut 32 thereon which may hold a wire against a washer or nut 33. On the inside of the bracket 27 is a spring 34 the lower end of which rests in a cup washer 35 that is threaded on a stem 36 which extends upward from the piston 26. The upper end of the stem is provided with a contact point 37 and a relatively light spring 38 is placed between the washer 35 and the upper surface of the plug 23 so that when the pressure is released the downward movement of 40 the cylinder by the spring 34 will not cause a knock of the washer 35 against the head of the plug. It will also be understood that this is only a typical arrangement as any similar device may be used.

45 50 It will be understood that other changes may be made without departing from the spirit of the invention. One of which changes may be in the use of other means for mounting a contact point upon a plug adapted to be inserted in the 55 cylinder of an engine, another may be in the use of other means for closing a circuit by pressure, and still another may be in the use of this device for a different purpose.

The construction will be readily understood from the foregoing description. In use this device may be made as shown and described and it will be noted that it may readily be placed in an engine cylinder and particularly in the head thereof 5 by tapping a hole in the cylinder or head and screwing the plug into the hole. The contact may then be connected to a light on the instrument board and set so that with the normal explosion pressure a contact will be made and the circuit 10 completed to light the light so that with one of these devices on each cylinder the lights may be lighted continuously as the engine is in operation and should the pressure in any cylinder fall below a certain amount or should any cylinder fail to 15 fire it will be immediately indicated by these lights on the instrument board. It will also be understood that this device may be installed upon an engine and set so that it only operates when desired, as a person may only desire to test the 20 engine at certain intervals or every morning or whenever he feels that it is not operating properly. It may, however, operate continuously. The device is particularly adapted for airplanes because the operator may readily determine 25 whether or not all of his cylinders are fired properly and if not which one is defective.

Having thus fully described the invention what I claim as new and desire to secure by Letters 30 Patent, is:—

35 A pressure operated circuit closing device of the type adapted to be mounted directly on a cylinder of an internal combustion engine, with the interior thereof opening into and communicating with the pressure and explosive chamber of said cylinder, comprising a plug having a cylinder 40 therein, and a threaded shank adapted to be screwed into a threaded opening extending through the cylinder wall like a spark-plug, a piston in the cylinder in said plug positioned to be operated directly by the pressure of the gases in the engine cylinder through an unobstructed passage, a rod extending from said piston through the outer end of said plug having a spring retaining cup threaded thereon, a yoke extending outward from said plug forming a cover for the outer end of said rod, a spring between the inner surface of said yoke and said cup positioned to urge 45 said piston inward, a relatively small shock absorbing spring around said piston rod between the cup and plug, a contact point adjustably mounted in said yoke, and positioned to engage the end of the said rod when the piston is moved outward by the pressure in the cylinder. 50
